(57) **CLAIM**

The ornamental design for a stand for handheld electronic device, as shown and described.

DESCRIPTION

FIG. 1 is a perspective view of a stand for handheld electronic device showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is the stand for handheld electronic device in a second configuration;

FIG. 9 is the stand for handheld electronic device in a third configuration; and,

FIG. 10 is the stand for handheld electronic device in a fourth configuration.

The lower portion of the stand is shown with symbolic breaks in its length. The appearance of any portion of the article between the two break lines forms no part of the claimed design. The broken lines immediately adjacent the shaded areas represent the bounds of the claimed design while all other broken lines are directed to environment and are for illustrative purposes only; the broken lines form no part of the claimed design.
